UNITED STATES PATENT OFFICE

2,548,098

FOLDING CHAIR KNEELER ATTACHMENT

John H. Clarin, Oak Park, Ill., assignor to Clarin Mfg. Co., Chicago, Ill., a corporation of Illinois

Application August 12, 1949, Serial No. 109,915

5 Claims. (Cl. 155—166)

1

This invention relates to folding chairs with kneeler attachment embodying improvements over the construction shown in Patent No. 1,846,392.

The main objects of this invention are to provide an improved form of kneeler attachment for folding chairs; to provide an improved form and arrangement of means for mounting a kneeling platform whereby the act of folding the chair into its storage position automatically swings the platform into coplanar relationship with the folded chair; and to provide an improved kneeler attachment of this kind which is more simple in construction, less expensive to manufacture, and renders the chair more comfortable in use than the construction shown in the aforementioned patent.

In the accompanying drawings:

Fig. 1 is a perspective view of a chair having an improved kneeler attachment constructed in accordance with this invention, the attachment being shown in its retracted position with the chair in its unfolded seating position;

Fig. 2 is a similar view of the chair but showing the kneeler attachment in its extended position for use;

Fig. 3 is a perspective view illustrating the relationship of the chair and kneeler attachment in the course of folding the chair and effecting a retraction of the kneeler attachment into its coplanar relationship therewith;

Fig. 4 is an enlarged, fragmentary rear view of the folded chair and kneeler attachment showing the linkage whereby the kneeler attachment is connected to the chair leg;

Fig. 5 is a side elevation of the chair and kneeler attachment in their folded coplanar relationship;

Fig. 6 is an enlarged side elevation of the view shown in Fig. 2; and

Fig. 7 is an enlarged, fragmentary cross-sectional detail taken on the line 7—7 of Fig. 6.

A folding chair 10, wherewith a kneeler attachment 11 embodying this invention is especially adapted for use, comprises a pair of leg frames 12 and 13 pivotally connected at 14 to form an X in extended or unfolded position and providing a support for a seat 15.

The leg frames 12 and 13 are formed from strips of sheet metal, the lateral edges of which have been turned inwardly to provide reinforcing beads 16 with a flat space between them.

Such a strip of material is bent into the form of a U to provide the frame 12 with the parallel portions spanned by cross braces 17 and 18 ad-

2

jacent to and on opposite sides of the pivot 14, The frame 12 provides the front legs and back support for the chair 10. At its upper end or base of the U is arranged a curved plate of sheet metal to constitute a back rest 19.

The frame 13 comprises a pair of these formed strips and constituting the rear legs 20 connected by a cross brace 21. Extensions 22 on these formed strips 20 have the seat 15 hinged thereto at 23. At their lower ends the legs 20 have bars 24 set in between the reinforcing beads 16 to strengthen the legs for the support of the linkage and levers which operatively connect the kneeler attachment 11 to the chair 10.

At their lower extremities the frames 12 and 13 have set therein rubber pads 25 of the type shown in Patent No. 2,137,803.

The seat 15 in addition to being pivoted at 23 to the extensions 22 of the frame 13, is suspended from the frame 12 by links 26. At their lower ends these links 26 are formed with shoulders 27 which contact the cross brace 17, when the chair is in its unfolded seating position, and limit the unfolding movement of the frames 12 and 13.

The kneeler attachment 11 comprises a platform 28 and a hinged foot support 29 connected by pairs of arms or links 30 and 31 to the lower ends of the rear chair legs 20. Levers 32 pivoted on the rear legs 20 are positioned to be engaged by the front chair legs when the chair is being folded into its storage position, and swing the attachment 11 from its horizontal rearwardly-disposed position into a retracted or collapsed coplanar position with respect to the folded chair frames 12 and 13.

The platform 28 may be a slab of wood or other suitable material secured to a frame 33. As best shown in Fig. 4, the frame 33 is a piece of strip metal bent to form a U with the ends of the parallel portions connected by a cross bar 33.1.

The foot section 29, as herein shown, is a metal strap bent to provide two U-shaped extensions 34, the ends of which are pivoted at 35 to the U-shaped frame 33 on the inside of the parallel portions adjacent the base or transverse part of said frame 33. Rubber pads 36 are secured to the bottoms of the U-shaped extensions 34.

The pairs of arms or links 30 and 31 are pivoted at 37 and 38 respectively to the lower ends of the rear legs 20. The arm or link 30 has its rear end pivotally connected to the platform 28 on an axis concentric with the hinge of the foot support

29 to the frame 33. The arm or link 31 is pivoted at 39 to the foot support slightly eccentric of the hinge connection thereof to the platform frame 33. A short link 40 is pivoted at 41 to the arm or link 31 and at 42 to the forward ends of the platform frame 33. This arrangement of the arms 30 and 31 disposes the platform 28 either in a horizontal plane or a vertical plane, with the foot support extended transversely to or folded against the bottom of the platform 28, depending upon whether the chair frames 12 and 13 are in their extended or folded positions.

The levers 32 are pivoted at 43 to the rear chair legs 20 above the pivots 37 and 38 for the arms or links 30 and 31. The rear end of each lever 32 is connected by a link 44 to an arm or link 30 rearwardly of its pivotal connection to the chair leg 20. The length of the link 44 is such as to dispose the lever 32 substantially parallel with the arms or links 30 and 31 (see Fig. 6) when the kneeler attachment 11 is in its extended position rearwardly of the chair 10, and ensure the contact of the front legs therewith exerting a downwardly-rearward pressure on the levers 32 to cause an upward swinging of the platform 28 when the chair 10 is folded.

At their forward ends each of the levers 32 is provided with an extension 45 bent to form opposed hooks 46 and 47 (see Fig. 7). The extension 45 is disposed at right angles to the lever 32, as most clearly shown in Figs. 2 and 6. The length of the shank between the two hooks is such that the base of the hook 46 is disposed below the under edge of the lever 32. Thus, in the folding of the chair 10 into its storage position the front legs of the frame 12 engage the hooks 46 and apply a pressure downwardly and rearwardly on the hook 46 which causes the levers 32 to automatically swing the platform 28 upwardly (see Fig. 3) into a coplanar position with the leg frames 12 and 13 in their completely-folded storage position, as shown in Fig. 5. Moreover, the disposition of the hooks 46 and 47 permit the legs to assume a fully coplanar relationship when folded for storage or transport.

The length and relative positioning of the arms or links 30 and 31 and the relative arrangement and connection of the levers 32 constitute critical factors in the mounting of the herein shown kneeler attachment.

In the arrangement of a kneeler attachment to a chair of this kind, two conditions have to be met. First, when the kneeler attachment is in its use position behind the unfolded chair, the distance A (see Fig. 6), rearwardly of a vertical plane B tangent to the rear upper edge of the back, must be such as to provide an acceptable posture for a person kneeling on the platform. Such posture is more likely to be acceptable when the kneeling person may lean slightly forward. Secondly, the most comfortable seating posture is when the seat is slightly inclined rearwardly. Mounting the seat to achieve such a rearward inclination limits the space between the lower ends of the legs and the forward edge of the seat in its folded position, and within which space the platform and its supporting linkage must be accommodated.

The kneeler attachment herein shown accomplishes this dual result.

From the foregoing it should be obvious that with the chair 10 in its unfolded seating position the kneeler attachment 11 may be freely swung manually between its extended use position, as shown in Fig. 2, and a coplanar relationship with

the leg frame 13, as shown in Fig. 1, as circumstances may require.

When it is desired to fold the chair 10 for storage or transport purposes, and the kneeler attachment is down in use position, the folding of the chair automatically retracts the kneeler attachment into coplanar relationship with the folding chair as indicated in Fig. 5. The folding of the chair causes the front legs to engage the respective hooks 46 on the levers 42 and depress said levers. This pressure causes the levers to swing the platform up into its retracted position.

As the platform 28 swings between its respective positions the foot support 29 is simultaneously swung between a position transverse to the platform in its use position and a retracted position against the platform when in its coplanar position with respect to the leg frame 13.

Although but one specific embodiment of this invention has been herein shown and described, it will be understood that details of the construction shown may be altered without departing from the spirit of the invention as defined by the following claims.

I claim:

1. The combination with a folding chair of a kneeler attachment, arms connecting said attachment to the rear legs of said chair to permit swinging of said attachment between a horizontal position rearwardly of said chair in its unfolded seating position and a retracted position with said chair in its folded storage position, a lever pivoted on one of said rear chair legs and disposed so as to be engaged by a front chair leg during the folding of said chair into its storage position, and a link operatively connecting said lever with one of said arms whereby said attachment is swung into retracted position by the folding of said chair.

2. The combination with a folding chair of a kneeler attachment comprising a platform, arms having their outer ends connected to said platform and their inner ends pivoted to the rear legs of said chair whereby said platform is swingable between a horizontal position rearwardly of said chair in its unfolded seating position and a retracted position with said chair in its folded storage position, a lever pivoted to one of said rear chair legs, a link connecting said lever to one of said arms, and means on said lever positioned to be engaged by a front chair leg during the folding of said chair into its storage position and swing said platform into said retracted position.

3. The combination with a folding chair of a kneeler attachment comprising a platform, arms having their outer ends connected to said platform and their inner ends pivoted to the rear legs of said chair whereby said platform is swingable between a horizontal position rearwardly of said chair in its unfolded seating position and a retracted position with said chair in its folded storage position, a lever pivoted to one of said rear chair legs, a link connecting the rear end of said lever to one of said arms, a hook formed on the forward end of said lever positioned to be engaged by a front chair leg below a horizontal plane through the axis of said lever pivot during the folding of said chair into its storage position and swing said platform into said retracted position.

4. The combination with a folding chair of a kneeler attachment comprising a platform, a support hinged on said platform to space the

same above the floor when in its use position, pairs of arms having their inner ends pivotally connected one above the other to the rear chair legs and having their outer ends pivoted respectively to said platform and said support to permit swinging of said platform between a horizontal position rearwardly of said chair when in its unfolded seating position with said support vertically disposed and a retracted position when said chair is in its folded storage position with said support folded against said platform, a lever pivoted intermediate its ends to one of said rear chair legs above the pivots of said arms, a link connecting the rear end of said lever to one of said arms, and means on the forward end of said lever positioned to be engaged by a front chair leg during the folding of said chair into its storage position and swing said platform into said retracted position.

5. The combination with a folding chair of a kneeler attachment comprising a platform, arms having their outer ends connected to said platform and their inner ends pivoted to the rear legs of said chair whereby said platform is swingable between a horizontal position rearwardly of said chair in its unfolded seating position and a re-

tracted position with said chair in its folded storage position, a lever pivoted to one of said rear chair legs, a link connecting said lever to one of said arms, means on said lever positioned to be engaged by a front chair leg during the folding of said chair into its storage position and swing said platform into said retracted position, a foot support hingedly mounted on said platform, and an arm connecting said foot support to said rear chair leg so as to effect a swinging of said foot support between a position perpendicularly disposed to said platform in its horizontal position and a position folded against said platform when in its retracted position with respect to said chair.
